WO WO8807962 10/1988

Primary Examiner — Ian Simmons

Assistant Examiner — Mark Cavanna

(57) CLAIM

The ornamental design for a child worry relief teaching kit, as shown and described.

DESCRIPTION

FIG. 1 is a front view of a child worry relief teaching kit showing my new design;

FIG. 2 is a rear view of the child worry relief teaching kit;

FIG. 3 is a left side view of the child worry relief teaching kit;

FIG. 4 is a right side view of the child worry relief teaching kit;

FIG. 5 is a top view of the child worry relief teaching kit; and,

FIG. 6 is a bottom view of the child worry relief teaching kit. The broken lines are included for the purpose of illustrating unclaimed portions of the child worry relief teaching kit and form no part of the claimed design.

1 Claim, 6 Drawing Sheets---
